J. B. MATTHEWS,

SILO AND THE LIKE BUILT OF WOODEN STAVES

FILED JULY 25 1910

UNITED STATES PATENT OFFICE.

JOHN B. MATTHEWS, OF PORTLAND, OREGON.

SILO AND THE LIKE BUILT OF WOODEN STAVES.

Application filed July 25, 1919. Serial No. 313,369.

To all whom it may concern:

Be it known that I, JOHN B. MATTHEWS, a citizen of the United States, and a resident of Portland, county of Multnomah, and 5 State of Oregon, have invented a new and useful Improvement in Silos and the like Built of Wooden Staves, of which the following is a specification.

My invention relates particularly to silos, 10 but in general to any container or housing built of wooden staves, arranged in horizontal tiers, connected along their longitudinal edges by tongue and groove joints, or the like, and having their abutting ends tied 15 together.

The general object of my invention is to provide an inexpensive, and at the same time an efficiently constructed, and dependable container of the class referred to.

20 I will describe my invention as applied to silos of the class referred to. These silos are generally built of angular cross-section, and it is of course essential that the joints of the staves be firmly tied together in permanent air tight relation.

The fundamental object of my invention is to obtain a silo or container of the class mentioned in which all rigid binding or non-yielding relationship of the parts shall be 30 avoided, since such cause undue compression, mashing and fractures, resulting in permanent crevices thru which air may enter the silo.

Briefly stated, I attain the objects of my 35 invention by holding the parts firmly together at their joints by means permitting the parts harmonious relative motion with each other, thereby eliminating all undue stress due to expansion and contraction, vibration or external pressure due to heavy winds; and thus eliminating all danger of fracturing the joints, or causing air crevices, or blowing over of the silo.

More specifically stated, I attain my object in the following features of my silo.

1. I build the body of staves provided with interlocking tongues and grooves along their longitudinal edges, or equivalent interlocking means including a groove adapted 50 to serve as a channel for holding tar or similar substance which the wood will not absorb to any great extent, and which tending to remain in semi liquid state, hence adhering

to the tongues inserted in the grooves and forming therewith air-tight joints.

2. By assuring the stability of the silo and the holding of the tiers of staves firmly mounted one upon the other, by weights hung from the uppermost tier of staves, and distributed about the sides of the silo; 60 preferably using weights greater than the total weight of the material of which the silo is built; thereby permitting the staves harmonious, relative, vertical motion with each other, and eliminating undue strain and stress due to expansion and contraction of the parts of vibration of the silo by the winds, and in so doing eliminating the danger of causing fractured joints, or air crevices, or the blowing over of the silo.

3. By tying the abutting ends of the staves firmly together, by clamps which accommodate any longitudinal expansion and contraction of the staves, but maintain their end joints in air-tight relation at all times.

4. By providing door frames which will accommodate the expansion and contraction of the stave ends terminating at the door opening, and yet assure efficient closure of the door opening.

The features above referred to are illustrated in the accompanying drawings in which:—

Fig. 1 is a perspective—more or less diagrammatic—of the body of my silo with which my invention is alone concerned; therefore the roof is omitted;

Fig. 2 is a vertical section thru the concrete base, the ground sill, and the lower part of one wall of my silo;

Fig. 3 is a plan, or top-edge view, of one corner of a tier of staves of which the walls of my silo are built; this view illustrates how the abutting ends of the staves are interlocked with each other, and tied together by clamps adapted to draw the staves together end-on and at the same time exerting an inward pressure upon the staves and walls of the silo;

Fig. 4 is a front elevation of the same parts and features illustrated in Fig. 3;

Fig. 5 is a fragmental perspective section of a similar corner illustrating other means for interlocking the abutting ends of the staves together;

Fig. 6 illustrates details of construction

whereby the abutting stave ends are adapted for interlocking with each other;

Fig. 7 shows a fragment of the silo wall provided with a door opening, and illustrates the preferred details of construction of the door-frame, and of the door or closure for the latter;

Fig. 8 is a section on the broken line 8—8 of Fig. 7;

10 Fig. 9 is a section on the broken line 9—9 of Fig. 7.

Figs. 10 and 11 are perspective fragments illustrating details of construction of the door-frame;

15 Fig. 12 is a detail of the means provided for securing and guiding the cables suspending the weights, whose function is to hold the tiers of staves firmly mounted on each other, and on the base, as illustrated in 20 Fig. 1; and

Fig. 13 is a detail of a "corrugated fastener" which is set transversely in the groove of the staves, so as to block the open ends thereof and retain tar, or other filling in the 25 groove.

The body *a* of my silo is mounted upon ground sill *b*, and the latter is preferably mounted upon a concrete base *c*, the sill and base being connected by tongues *d*. The 30 walls of the body *a* are built of wooden staves *e*, arranged horizontally in tiers, and provided with a groove *f* and tongue *g*, respectively, along their longitudinal edges.

The staves are so arranged that their 35 grooves 24 are up, since the latter are utilized also as channels for holding a filling of tar or similar substance, not absorbed by the wood to any great extent, and adhering to the tongues, thereby forming an air-tight elastic joint; the open ends of the 40 grooves being blocked by little plates commercially known as "corrugated fasteners" (see Fig. 13) set transversely in the grooves, as illustrated in Figs. 10 at 25.

45 In order firmly to hold the abutting ends of the staves in interlocked relation, I prefer to employ the means disclosed in Figs. 3, 4, 5, and 6.

In Figs. 3, 4, 6, the stave-end *h* is shown 50 as made square, thus locating the end face *i*, in a plane forming an acute angle with a plane radial to the longitudinal axis of the silo. The stave-end *j* is formed with a rectangular recess *j*² adapted for having the 55 square stave-end *h* seated therein; and one wall of said recess is made with a projecting lip at the interior, as shown at *j*¹ in Figs. 3 and 6, constituting a shoulder against which bears the inner face of the stave-end *h*, and serving to hold the latter against inward movement.

By interlocking the abutting stave-ends in the manner shown in Fig. 3, neither stave-end can move away, inward or outward, 65 from the related abutting stave-end so long

as the staves are firmly drawn together end-on, and thus maintaining an air tight joint.

In order to obtain such end-on compression, I tie the abutting ends of the staves together by clamps constructed as illustrated 70 in Figs. 3 and 4.

These clamps consist of a short part *k*, and a long part *l*, each part being made of heavy wire. The short part *k* is formed so as to provide a perpendicular eye *m*, and 75 two legs, the extremities *n* of which are bent at an acute angle (see Fig. 3) to constitute claws seated in holes therefor provided in the stave-ends. The larger clamp part *l* is formed to provide a perpendicular eye *o*, the portions *p* adjacent such eye are bent at an obtuse angle as shown in Fig. 3, and the extremities *q* of the legs are bent at an acute angle constituting claws similar to the extremities *n* of the clamp part *k*, and being seated in holes therefor provided in the stave-end. Plates *r* are placed on said legs adjacent the eye *m*, *o*, and a bolt and nut *s* is inserted thru the latter. Hence by drawing up the nut of the bolt *s*, the abutting stave ends are drawn firmly together, and at the same time the bent portion or shoulder *p*, of the clamp-part *l* exerts an inward pressure upon the abutting stave ends, and thus upon the silo wall, thereby 90 resisting and neutralizing the outward pressure of the contents of the silo and preventing the jointed stave-ends from warping.

The claws of the clamps are located only a short distance from the ends of the staves, and therefore the elasticity inherent in the material of which the clamps are made is sufficient to accommodate, and take up the slight longitudinal expansion and contraction of the staves.

In Fig. 5 I have shown another means for interlocking the abutting stave-ends. As shown in the latter figure the staves *e'* are provided along their abutting vertical edges with grooves 26 in which is seated a rod or key *t*. These abutting staves ends are tied and drawn together by clamps similar in construction and operation to those shown in Figs. 3 and 4.

The doors of my silo I preferably construct as follows:—

The door opening is made rectangular as usual. At the sides of the door opening vertical frame members 3 are pivotally fastened at their middle, to the ends of the staves *e'*, located in the vertical middle of the door opening (see Figs. 7, 8, 9, and 11), and horizontal door-frame members 7, 8 are fastened to the staves *e'* and *e*² located at the upper and lower ends of the door opening.

The ends of said upper and lower door-frame members 7, 8, have fastened on them, plates 9, by bolts 9²; and the extremities of said plates are bent to provide perpendicular 130

clamping-ends 10 having engagement with the related ends of the horizontal door-frame members.

The ends of the vertical door frame members are fastened to the staves terminating at the door opening by clamps 5. These clamps are similar in construction to the short clamp-part *k* of the clamps illustrated in Figs. 3 and 4, having an eye thru which 10 is inserted a bolt 6, threaded into the vertical frame-member 3 as shown in Figs. 7 and 11.

My object in the described door-frame construction is to permit the staves of the 15 wall adjacent the door-opening to have vertical movement under the ends of the vertical frame members 3.

The door-body is made of stave pieces 11 provided with tongue and groove, interlocking, longitudinal edges, the same as the staves of the body of the silo. The staves of the door-body are preferably tied together by clamps consisting of two parts 12, 13 in construction similar to the clamp-part *k* of 20 the clamps shown in Figs. 3 and 4, and drawn together by bolts and nuts 14 (see Fig. 7).

In order to firmly and tightly seat the vertical edges of the staves of the door body, 30 the latter are beveled as shown at 15 in Fig. 9; and the abutting end faces of the staves terminating at the door opening are correspondingly beveled.

The door is firmly drawn into place by 35 means of bolts 16 fastened at one end in the door-body and having its free ends threaded and projecting thru an angle-plate 17; and on the threaded extremities of the bolts 16 are screwed latch-bars 18. See Figs. 7 and 8.

The tiers of staves of which the body of the silo is constructed are held firmly mounted one upon the other by the pull of the 45 weights 19, suspended by cables 20 running through pulleys 21 supported by clamps 22; the upper ends of the cables being fastened to the uppermost tier or crown of the silo body, and the upper cable-ends are crossed to constitute a brace; as shown in Fig. 1.

I believe the best result is obtained by 50 using weights whose total weight is greater than the total weight of the material of which the silo is built. The excess of weight over the other must be left to selection, taking into consideration the usual weather 55 conditions of the locality in which the silo is to be erected and the weights must be arranged close to the ground, as shown, thus below the centre of gravity of the silo body.

The staves 11 of the body of the door are 60 preferably also tied together by vertical thru-bolts 11^a (see Fig. 9).

The upper horizontal door frame member 7 projects below the stave *e*⁴ to which it is 65 fastened; and the lower horizontal door-

frame member projects above the stave *e*⁴ to which it is fastened.

To prevent rain beating in over the lower horizontal door frame member, I provide the lowermost stave of the door body with a 70 projecting ledge or water-table 23.

The door construction shown at *v* in Fig. 1 is similar to that of the door construction *u*, except that the staves 11 of which the body of the door is put together are merely loosely 75 inserted, and are held in place by the pressure of the ensilage contained in the silo.

The roof of the silo is not shown or described since any convenient type of roof may be used in connection with the silo; my 80 invention not concerning the roof.

I claim:

1. A silo built of wooden staves arranged horizontally in tiers one above the other, the longitudinal edges of the staves of adjacent tiers being interlocked by a tongue-groove joint, the tongues of the overlying staves bearing in the grooves of the underlying staves, and weights suspended from the top of the container and distributed about the 85 sides thereof, thereby firmly holding said tongues in said grooves, the weight suspending means being adapted to permit the staves 90 harmonious, relative, vertical movement, thereby accommodating any sway of the silo 95 due to wind pressure, or the expansion and contraction due to heat.

2. A silo built of wooden staves arranged horizontally in tiers one above the other, the longitudinal edges of the staves of adjacent tiers being interlocked by a tongue-groove joint, the tongues of the overlying staves bearing in the grooves of the underlying staves, and weights suspended from the top of the container and distributed about the 100 sides thereof, thereby firmly holding said tongues in said grooves, but permitting the staves harmonious, relative vertical movement, said suspended weights being greater 105 than the total weight of the material of which the container is constructed, and said weights being arranged below the centre of gravity of the silo body for the purpose set forth.

3. A silo built of wooden staves arranged horizontally in tiers one above the other, the longitudinal edges of the staves of adjacent tiers being interlocked by a tongue-groove joint, the tongues of the overlying staves bearing in the grooves of the underlying staves, and weights suspended from the top of the container and distributed about the sides thereof, thereby firmly holding said tongues in said grooves, but permitting the 110 staves harmonious, relative, vertical movement, the suspending means of said weights consisting of cables fastened at their upper ends to the top of the container and thence being lead cross wise from the top down thru pulley-elements fastened to the middle por- 115 120 125 130

tion of the container and spaced apart in horizontal plane, said weights being arranged close to the ground.

4. A silo built of wooden staves arranged horizontally in tiers one above the other, the longitudinal edges of the staves of adjacent tiers being interlocked by a tongue-groove joint, the tongues of the overlying staves bearing in the grooves of the underlying staves, and weights suspended from the top of the container and distributed about the sides thereof, thereby firmly holding said tongues in said grooves, but permitting the staves harmonious, relative, vertical movement, said suspended weights being greater than the total weight of the material of which the container is constructed, the suspending means of said weights consisting of cables fastened at their upper ends to the top of the container and thence being lead cross wise from the top down thru pulley-elements fastened to the middle portion of the container and spaced apart in horizontal plane, and said weights being arranged close to the ground.

5. A silo built of wooden staves arranged in horizontal tiers, metal clamps tying the staves together, said clamps comprising two parts each constituting legs terminating at one end in a perpendicular eye and the other ends being bent at an angle which constitute claws and which can be inserted in the staves adjacent their ends, and a screw bolt inserted in said eyes adapted to draw said clamp parts together.

6. A silo built of wooden staves arranged in horizontal tiers, metal clamps tying the staves together, said clamps comprising two parts each constituting legs terminating at one end in a perpendicular eye and the other ends being bent at an angle which constitute claws and which can be inserted in the staves adjacent their ends, a screw bolt inserted in said eyes adapted to draw said clamp parts together, one of said clamp parts being longer than the other having a bent end overlapping the joint between abutting staves thereby exerting an inward pressure on said joint.

50 7. A silo built of wooden staves arranged in horizontal tiers, metal clamps tying the staves together, said clamps comprising two parts each constituting legs terminating at one end in a perpendicular eye and the other ends being bent at an angle which constitute claws and which can be inserted in the staves adjacent their ends, a screw bolt inserted in said eyes adapted to draw said clamp parts together, the legs of said clamp parts being spread so as to distribute the pull of the clamps over the entire width of the stave.

8. A silo built of wooden staves arranged in horizontal tiers, metal clamps tying the staves together, said clamps comprising two

parts each constituting legs terminating at one end in a perpendicular eye and the other ends being bent at an angle which constitute claws and which can be inserted in the staves adjacent their ends, a screw bolt inserted in said eyes adapted to draw said clamp parts together one of said clamp parts being longer than the other having a bent end overlapping the joint between abutting staves thereby exerting an inward pressure on said joint, the legs of said clamp parts being spread so as to distribute the pull of the clamps over the entire width of the stave.

9. A silo built of wooden staves arranged in horizontal tiers, one of the abutting ends of the staves being provided with a recess and the other end being square and adapted for seating in the abutting recess, one wall of the latter having a projecting lip constituting a shoulder restraining the inward movement of the stave and seated in said recess, metal clamps tying the staves together, said clamps comprising two parts each constituting legs terminating at one end in a perpendicular eye and the other ends being bent at an angle which constitute claws and which can be inserted in the staves adjacent their ends, a screw bolt inserted in said eyes adapted to draw said clamp parts together, one of said clamp parts being longer than the other having a bent end overlapping the joint between abutting staves thereby exerting an inward pressure on said joint.

10. A silo built of wooden staves arranged in horizontal tiers, one of the abutting ends of the staves being provided with a recess and the other end being square and adapted for seating in the abutting recess, one wall of the latter having a projecting lip constituting a shoulder restraining the inward movement of the stave end seated in said recess, metal clamps tying the staves together, said clamps comprising two parts each constituting legs terminating at one end in a perpendicular eye and the other ends being bent at an angle which constitute claws and which can be inserted in the staves adjacent their ends, a screw bolt inserted in said eyes adapted to draw said clamp parts together, one of said clamp parts being longer than the other having a bent end overlapping the joint between abutting staves thereby exerting an inward pressure on said joint, the legs of said clamp parts being spread so as to distribute the pull of the clamps over the entire width of the stave.

11. Stave clamp consisting of two parts made of heavy wire, each part being formed to provide diverging legs, and the connecting portion of said legs being formed into a perpendicular eye, the extremities of the legs being bent at an acute angle to provide claws, and screw-bolt inserted thru

said eyes of the clamp-parts for drawing the latter together.

12. Stave clamp consisting of two parts made of heavy wire, each part being formed to provide diverging legs, and the connecting portion of said legs being formed into a perpendicular eye, the extremities of the

legs being bent at an acute angle to provide claws, perforated plates placed on said eyes, and screw-bolt inserted through said eyes 10 of the clamp-parts for drawing the latter together.

JOHN B. MATTHEWS.
